UNITED STATES PATENT OFFICE.

EMIL G. SAUER, OF RICHMOND HILL, NEW YORK, ASSIGNOR TO BIGELOW CARPET COMPANY, A CORPORATION OF MASSACHUSETTS.

DESIGN FOR CARPET.

41,651.

Specification for Design.

Patented Aug. 1, 1911.

Application filed June 1, 1911. Serial No. 630,686. Term of patent $3\frac{1}{2}$ years.

To all whom it may concern:

Be it known that I, EMIL G. SAUER, a citizen of the United States, residing at Richmond Hill, in the county of Queens and State of New York, have invented a new, original, and ornamental Design for a Carpet, of which the following is a specification, reference being had to the accompanying drawing, forming part thereof.

The drawing illustrates a portion of a carpet showing my new design.

I claim:

The ornamental design for a carpet, as shown.

EMIL G. SAUER.

Witnesses:

DAVID G. BARRY,
THOMAS P. COSTELLO.
